CANDLE-MOLDING MACHINE.

1,268,530.

Specification of Letters Patent. Patented June 4, 1918.

Application filed October 19, 1915. Serial No. 56,776.

To all whom it may concern:

Be it known that I, FREDERICK F. ZIMMER, a citizen of the United States, and a resident of Syracuse, in the county of Onondaga and 5 State of New York, have invented a certain new and useful Candle-Molding Machine, of which the following is a specification.

This invention relates to candle molding 10 machines, and has for its object a particularly simple and efficient means for connecting the core members and the stripper members to their actuating means, and the invention consists in the combinations and 15 constructions hereinafter set forth and claimed.

In describing this invention, reference is had to the accompanying drawings in which like characters designate corresponding 20 parts in all the views.

Figure 1 is a fragmentary sectional view, partly in elevation, of one form of machine embodying my invention.

Fig. 2 is a fragmentary view of parts 25 seen in Fig. 1, showing the position of the core member and the actuator therefor when the core member is withdrawn below the upper surface of the candle.

Fig. 3 is a fragmentary view similar to 30 Fig. 2 showing the position of the stripper member and its actuator when the stripper member is operated to remove the candle from the die.

1 designates a gang of dies suitably supported by a frame 2.

3 is a core member, and 4 is a stripper member, movable reciprocally in each die, and arranged in concentric relation and having stems 5, 6 extending to the outside of 40 the die and connected to suitable actuating means.

7 is the top plate of the die, which plate forms the top of the candle.

8 and 9 are actuators for the stems 5 and 45 6 respectively.

The mechanism, as thus far described, in itself, forms no part of this invention, but, as will be understood by those skilled in the art, is common to this type of candle molding machines.

The operation of the machine as thus far described, is as follows:—

The molten grease or wax is poured into the dies 1 when the parts are in their position shown in Fig. 1, with the core mem-

bers 3 projecting slightly above the tops of the candles and the upper faces of the plates 7. After the dies 1 are filled, and the wax or grease has hardened, the actuator 8 is depressed into the position shown in Fig. 60 2, to withdraw the upper end of the core rods 3 below the upper surfaces of the top plates 7. The candles are then trimmed off to the level of the upper faces of the top plates 7. The actuator 9 is then actuated to 65 cause the strippers 7 to remove the molded candles as shown in Fig. 3. The passages left by the core members 3 are for the purpose of inserting the wicks, as will be understood by those skilled in the art. The 70 actuators 8, 9 are operated by any well known mechanism.

This invention relates to means for connecting the stems 5, 6 to their actuators whereby they can be readily disconnected 75 or again connected to said actuators. In this form of my invention the actuators 8, 9 are formed respectively with keyways 10, 11, and the stems 5, 6 run contiguous to each other, and are preferably arranged in concentric relation, with one gang or set of stems, as the inner set 5, longer than the other or outer set 6. Both sets or gangs of stems 5, 6 extend transversely through the keyway 11 of the actuator 9 for the shorter 80 stems 5, and the longer set or gang of stems 6 extend through said actuator 9 for the shorter stems, the longer stems 5 being formed with lengthwise slots 12 in the portions thereof traversed by the 85 actuator 9 for the shorter stems. A key 13 common to all the shorter stems, passes lengthwise of the keyway 11 through the shorter stems and through the slots 12 in the longer stems 5.

The stems 5 are secured to their actuator 8 by a key 14 similar to the key 13, the key 14 extending lengthwise of the keyway 10 and through the lower ends of the stems 5. Heretofore, each of the stems has had its 90 own individual connection to its actuator and hence it required considerable time to remove the core and stripper members and to replace the same. In this machine all the core and stripper members can be readily 95 removed upon the withdrawal of the keys 13 and 14 and when replaced can be held in position by the insertion of these two keys. The keys 13 and 14 are normally held from accidental displacement by plates 15, 16 ex- 100 105 110

tending across the ends of the keyways 11, 10, respectively, these plates being held in position by screws 17, 18. Said plates must be removed prior to the withdrawal of the 5 keys.

What I claim is:

1. A candle molding machine comprising a gang of dies, a core member and a stripper member movable in each die and having 10 stems extending outside of the die, an actuator common to the stems of the core members, an actuator common to the stems of the stripper members, each actuator having a lengthwise keyway into which the companion stems extend, and a key extending 15 lengthwise of the keyway of each actuator and through the companion stems for coupling the stems to the actuator, substantially as and for the purpose specified.
- 20 2. A candle molding machine comprising a gang of dies, a core member and a stripper member movable in each die and having stems extending outside the die and arranged contiguous to each other, one set of 25 stems being longer than the other, actuators for the stems respectively, the longer stems extending through, and being slidable in, the actuator for the shorter stems, means common to all the shorter stems for connecting the same to their actuator, and means common to all the longer stems for connecting said longer stems to their actuator, substantially as and for the purpose set forth.
- 30 3. A candle molding machine comprising 35 a gang of dies, a core member and a stripper member movable in each die and having stems extending outside of the die and arranged contiguous to each other, one set of the stems being longer than the other, an 40 actuator common to the shorter stems, an actuator common to the longer stems, the actuator for the shorter stems being formed with a lengthwise keyway into which the shorter stems extend and through which the 45 longer stems pass, and a key passing lengthwise of the keyway and through the shorter stems to couple the shorter stems to their actuator, substantially as and for the purpose described.
- 50 4. A candle molding machine comprising 55 a gang of dies, a core member and a stripper member movable in each die and having stems extending outside of the die and arranged contiguous to each other, one set of the stems being longer than the other, an 60 actuator common to the shorter stems, an actuator common to the longer stems, the actuator for the shorter stems being formed with a lengthwise keyway into which the 65 shorter stems extend and through which the longer stems pass, a key passing through the keyway and through the shorter stems to couple the shorter stems to their actuator, the actuator for the longer stems being formed with a lengthwise keyway into which

the longer stems extend, and a key passing lengthwise of the latter keyway and through the longer stems, substantially as and for the purpose specified.

5. A candle molding machine comprising 70 a die, a core member and a stripper member movable in the die and arranged in concentric relation and having concentric stems extending to the outside of the die, one set of the stems being longer than, and extending 75 beyond, the other, actuators for the stems, the actuator for one stem having a keyway through which both stems extend transversely, and one of the stems being formed with lengthwise slots, and a key for securing 80 the other stem to its actuator, the key extending through the slot of the former stem, substantially as and for the purpose set forth.

6. A candle molding machine comprising 85 a gang of dies, a core member and a stripper member movable reciprocally in each die and having stems extending outside of the die and arranged in concentric relation, one set of the stems extending beyond the other, a 90 common actuator for the stems of the core members, a common actuator for the stems of the stripper members, the actuator connected to the shorter stems being formed with a lengthwise keyway into which the 95 shorter stems extend and through which the longer stems pass transversely, and the longer stems being formed with lengthwise slots, and a key common to all the shorter stems, the key extending lengthwise of the 100 keyway and through the slots of the longer stems, substantially as and for the purpose described.

7. A candle molding machine comprising 105 a gang of dies, a core member and a stripper member movable reciprocally in each die and arranged in concentric relation with each other, said members having stems extending outside of the die and located one within the other, and the inner stem extending beyond 110 the outer stem, actuators connected respectively to the gangs of stems, the inner stems being formed with lengthwise slots, and a key for securing the outer stems to their actuator, said key extending transversely 115 through the slots of the inner stems, substantially as and for the purpose specified.

8. In a candle molding machine, the combination of a gang of dies, a core member, and a stripper member movable in each die 120 and arranged in concentric relation, said members having stems extending outside of the die and arranged one within the other, the inner stems being longer than the outer stems, a common actuator for the stems of 125 the stripper members, a common actuator for the stems of the core members, the actuator for the shorter outer stems being formed with a keyway through which all the stems extend transversely and the inner longer 130

5 stems being formed with lengthwise slots in the portions thereof traversed by the actuator for the shorter outer stems, and a key common to all the outer stems and extending lengthwise of the keyway of the actuator for the outer stems through said outer stems and through the slots of the inner stems, substantially as and for the purpose set forth.

9. A candle molding machine comprising
10 a gang of dies, a core member and a stripper member movable reciprocally in each die and having stems extending outside of the die and arranged in concentric relation, one stem being longer than, and projecting beyond, 15 the other, the longer stems being provided with lengthwise slots, a common actuator for the shorter stems, a common actuator for the longer stems, said actuators being each

formed with a lengthwise keyway, both sets of stems extending transversely through the 20 keyway of the actuator for the shorter stems and the longer stems extending transversely into the keyway of the actuator for said longer stems, a key extending lengthwise of the keyway of the first-mentioned actuator 25 through the shorter stems and through the slots of the longer stems, and a key extending lengthwise of the actuator for the longer stems and through said longer stems, substantially as and for the purpose described. 30

In testimony whereof, I have hereunto signed my name, at Syracuse, in the county of Onondaga, and State of New York, this 24th day of Sept., 1915.

FREDERICK F. ZIMMER.
